(57) CLAIM

The ornamental design for a handle for implant delivery device, as shown and described.

DESCRIPTION

FIG. 1 is a perspective view of a handle for an implant delivery device, as viewed from the distal end and the left side thereof.

FIG. 2 is a perspective view of the handle of FIG. 1, as viewed from the proximal end and right side thereof.

FIG. 3 is a left side elevation view of the handle of FIG. 1.

FIG. 4 is a right side elevation view of the handle of FIG. 1.

FIG. 5 is an elevation view of the distal end of the handle of FIG. 1.

FIG. 6 is an elevation view of the proximal end of the handle of FIG. 1.

FIG. 7 is a top plan view of the handle of FIG. 1.

FIG. 8 is a bottom plan view of the handle of FIG. 1; and, FIG. 9 is a cross-sectional view taken along line 9-9 of FIG. 3.

The dash-dash broken lines in the drawings are for purposes of illustrating portions of the handle for implant delivery device that form no part of the claimed design.
